1927

UNITED STATES PATENT OFFICE.

JENNIE SHEILS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 18,171, dated March 6, 1888.

Application filed January 11, 1888. Serial No. 260,448. Term of patent 3½ years.

To all whom it may concern:

Be it known that I, JENNIE SHEILS, of the city, county, and State of New York, have invented and produced a new and original Design for a Pattern of a Lady's Costume; and I do hereby declare that the engraved prints accompanying this specification convey to any one accustomed to using paper patterns a clear understanding of how a garment made up by 10 the pattern will appear.

The design shows a basque and round walking-skirt. The skirt displays a plain front panel having three pointed strap extensions, which lap upon upright plaits in a panel at 15 either side, a short round tablier upon the front panel displaying plaits in its side edges and pointed straps extending upon it from under either side panel, and a full back drapery that falls even with the edge all across and

exhibits two loopings at the center near the 20 top. The basque displays the right front lapping diagonally upon the left and shaping two pointed straps above the bust, a close-fitting back that displays the center seam terminating at the top of an underfolded box-plait, and 25 the side backs lapping upon the lower part of the back skirt, coat-sleeves with strap ornaments at the wrists, and a standing collar.

What I claim as my invention, and desire to 30 secure by Letters Patent, is—

The design for a lady's costume, as shown in the engraved prints accompanying this specification.

JENNIE SHEILS.
